(57) **CLAIM**

The ornamental design for a staple driving tool, as shown and described herein.

DESCRIPTION

FIG. 1 is a top front perspective view of a staple driving tool of one embodiment of my new design.

FIG. 2 is a bottom front perspective view of the staple driving tool of my new design illustrated in FIG. 1.

FIG. 3 is a top rear perspective view of the staple driving tool of my new design illustrated in FIG. 1.

FIG. 4 is a bottom rear perspective view of the staple driving tool of my new design illustrated in FIG. 1.

FIG. 5 is a front view of the staple driving tool of my new design illustrated in FIG. 1.

FIG. 6 is a rear view of the staple driving tool of my new design illustrated in FIG. 1.

FIG. 7 is a left side view of the staple driving tool of my new design illustrated in FIG. 1.

FIG. 8 is a right side view of the staple driving tool of my new design illustrated in FIG. 1.

FIG. 9 is a top view of the staple driving tool of my new design illustrated in FIG. 1; and,

FIG. 10 is a bottom view of the staple driving tool of my new design illustrated in FIG. 1.

The portions shown in phantom is not part of the design sought to be patented and is provided for environmental purposes only.

1 Claim, 10 Drawing Sheets
